FIG. 3

FIG. 1 is a front elevational view of the basic lighting fixture showing the preferred embodiment of my new design;

FIG. 2 is a bottom plan view of the lighting fixture shown in FIG. 1; and

FIG. 3 is a top plan view of the lighting fixture shown in FIG. 1.

As will be seen in FIGS. 1-3 the lighting fixture embodying my new design is four-sided and has the same appearance from the front, rear and from the sides.

The hammered surface texture is partially shown in FIGS. 2 and 3 for convenience of illustration and is understood to be uniformly continuous over the surface of the fixture.

It is to be understood that the surface of my new design is not limited to a hammered surface texture, that is, the surface may be smooth.

I claim:
